PLAYEE COMPANY, OF ROCK ISLAND, ILLINOIS, A CORPORATION OF ILLINOIS.

COMBINED RECORD-REWINDING, SHIFTING MECHANISM, AND RELIEF FOR PIANO
PLAYING ATTACHMENTS.

1,032,451.

Specification of Letters Patent. Patented July 16, 1912.

Application filed February 28, 1908. Serial No. 418,367.

To all whom it may concern:

Be it known that I, EUGENE T. TURNER, a citizen of the United States, residing at Rock Island, in the county of Rock Island 5 and State of Illinois, have invented certain new and useful Improvements in Combined Record - Rewinding, Shifting Mechanism, and Reliefs for Piano-Playing Attachments, of which the following is a specification.

10 This invention relates to improvements in combined record re-winding, shifting mechanism and relief for piano playing attachments, in which there is employed a plurality of pneumatic actions having communication with air ducts or channels and which latter are adapted to be exhausted to operate the pneumatics, and a record operating mechanism, which latter is adapted to be shifted to re-wind the record after the 15 latter has been used, and the primary object of the invention is to provide improved means for shifting the re-winding mechanism and improved means for simultaneously relieving the air ducts or channels, 20 whereby the pneumatics will be prevented from acting during the re-winding of the record, which will prevent the operation of the keys of the instrument and sounding the 25 notes.

30 A further object is to provide improved positive means for simultaneously shifting the re-winding mechanism and relieving the air ducts or channels.

35 A further object is to provide an improved device of this character which will be simple, durable and cheap in construction and effective and efficient in operation.

To the attainment of these ends and the 40 accomplishment of other new and useful objects, as will appear, the invention consists in the features of novelty in the construction, combination and arrangement of the several parts hereinafter more fully described and claimed and shown in the accompanying drawing, illustrating an exemplification of the invention, and in which—

45 Figure 1 is a detail elevation partly in section, of an improved device of this character constructed in accordance with the 50 principles of this invention. Fig. 2 is a detail top plan view taken on line 2—2 of Fig. 1, looking in the direction of the arrows. Fig. 3 is a detail sectional view on line 3—3 of Fig. 1. Fig. 4, is a detail sectional view

showing the relief valve in its adjusted position. Fig. 5 is a detail top plan view of the key for adjusting and holding the parts in their adjusted position.

Referring more particularly to the drawing and in the present exemplification of the invention the numeral 10 designates suitable air ducts or channels which have communication with each other through a chamber 11, and these channels may be exhausted through the chamber 11 by means of a tubular member 12 which has communication with a suitable exhaust chamber or chest. Supported by these air ducts or channels 10 and communicating therewith are pneumatic actions 13 which have communication with the tracker board (not shown) by means of the flexible tubular connections 14, so that when an opening in the record passes over the apertures in the tracker board, the respective pneumatics will be operated by the suction created in the air ducts or channels 10 in the manner set forth in my application for a patent, Serial No. 331,740, filed in the United States Patent Office August 23, 1906, and of which application the above construction and operation form the subject matter.

Supported in any suitable manner by the frame of the instrument is a record holding frame 15, (a portion only of which is shown) and journaled in the frame is a record receiving roller upon which the record 17 is adapted to be wound from the roller 16 and across the tracker board 17, when the roller 16 is operated by the flexible shaft 18 through the medium of the pinion 19 and the gear 20, which latter is secured to the roll 16 and with which the pinion 19 meshes.

An adjustable support 21 is provided for one end of the flexible shaft 18 and this support is movable in the record holding frame 15, and is provided with a guide 22 at its lower extremity which passes through a suitable aperture in the base of the frame 15, and a flexible member 23 is secured to the base of the frame and engages the guide 22 for normally holding the support 21 in an elevated position so that the pinion 19 will mesh with the gear 20. A suitable gear 24 is secured upon and for rotation with the flexible shaft 18 and a chain or belt 25 passes over the gear 24 and a gear 26 secured

to a stub shaft 27 which is journaled in the guide 21, and a clutch member 28 is also secured to the stub shaft 27 and adapted to engage and coöperate with another clutch member 29, which is connected to the roller 16^a. When the guide 21 is in a position to permit the pinion 19 to mesh with the gear 20, the chain 25 will be loose and the record will be fed from the roller 16^a to the roller 16, but when the support 21 is lowered against the tension of the flexible member 23 to cause the clutch member 28 to engage the clutch member 29 to lock the roller 16^a for rotation with the stub shaft 27, the pinion 19 will be moved out of engagement with the gear 20 and the chain 25 will be tightened so that the rotation of the shaft 18 will be imparted to the roller 16^a to re-wind the record upon the roller 16^a. The specific construction of the above referred to parts and the operation thereof form no part of the present invention but form the subject matter of an application filed by me on September 23, 1907, Serial No. 394,020, which application is a division of the application above referred to.

When the record 17 is being re-wound upon the roller 16^a, the suction in the air ducts or channels 10 continues and as the openings in the record pass over the respective openings in the tracker board, the pneumatics 13 would if not prevented be operated and thereby sound the notes as well as operate the keys. In order to prevent the sounding of the notes and the operation of the keys by the pneumatics 13 when the record is being re-wound, there is provided in one of the air ducts or channels 10 an aperture or opening 30 which has communication with the outside air, and a valve 31 is provided for closing the aperture. Any form of valve may be provided for closing the aperture but the preferred form of valve comprises a member having two faces 32, 33, on the lower side thereof, which diverge from a point adjacent the center of the valve to the extremities thereof so that when one face of the valve 31 rests upon the air duct or channel 10, the other face will be held out of engagement therewith.

A suitable flexible member 34, such as leather or the like, is secured to the face 33 of the valve and extends over but is free from the face 32. The portion of the flexible member 34 which extends adjacent the face 32 is secured to the top of the air duct or channel 10, as shown more clearly in Fig. 1 of the drawing, and this portion of the flexible member 34 serves as a hinge for the valve 31 to rock upon. The member 34 is provided with an aperture or opening 35 which is adapted to register with the aperture 30 in the air duct or channel 10. When the valve is in the position shown in Fig. 1, the face 32 will close the registering apertures

35, 30 in the member 34 and the air duct or channel 10, so that when the air ducts or channels are being exhausted the respective pneumatics 13 will be operated, but when the valve 31 is moved from the position shown in Fig. 1 to that shown in Fig. 4 so that the face 33 thereof will rest upon the air duct or channel 10, the aperture 30 in the air duct or channel will be opened so that as the air ducts or channels are being exhausted the outside air will be drawn into the air duct or channel through the aperture 30 to supply sufficient air to prevent the pneumatics 13 from being operated under the influence of the exhaust.

Any suitable means may be provided for operating the valve 31 to open the aperture 30. A suitable and efficient means for accomplishing this purpose comprises a bar or rod 36 which may be supported in any desired or suitable manner with one end adjacent one end of the valve 31 and the other end passing loosely through a portion 37 of the casing of the instrument. Secured to the bar or rod 36 and adjacent the valve 31 is a laterally projecting finger 38 which extends over one extremity of the valve 31, preferably the extremity adjacent the face 33, and is so located that when the valve or rod 36 is in an elevated position, the projection 38 will not interfere with the closing of the aperture 30 by the face 33 of the valve.

The extremity 39 of the valve or rod which passes through the portion 37 of the casing, is preferably threaded, and mounted upon this threaded extremity is an adjustable nut or collar 40 which is adapted to stand a slight distance from the lower face of the portion 37 of the casing when the bar or rod 36 is in its normal position. Slidably mounted upon the lower face of the portion 37 of the casing is a key or member 41, which is secured against displacement by means of suitable screws or bolts 42 passing through slots 43 in the key 41 and into the casing 37. One extremity 44 of this key or member is bifurcated as at 45 and is provided with an inclined face 46, which latter normally stands adjacent the bar or rod 36. An operating handle 47 may be provided on the opposite end of the key 41, by means of which the latter may be adjusted to cause the inclined face 46 to engage the nut or collar 40 to depress the rod 36 and cause the lateral projection 38 to engage the extremity of the valve 31 and rock the same from the position shown in Fig. 1 to the position shown in Fig. 4 to uncover the aperture 30 in the air duct or channel, the rod 36 being adapted to enter the bifurcation 45 in the extremity 44 of the key 41 and when so adjusted the valve 31 will be locked in this position by the key 41 until the latter is moved to its original position to disengage

the nut or collar 40. When thus released, the suction in the air duct or channel 10 will draw the face 32 of the valve 31 downwardly so as to close the aperture 30.

5 Any suitable means may be provided for simultaneously shifting the flexible shaft 18 so as to disengage the pinion 19 from the gear 20 to tighten the chain 25 for re-winding the record upon the roller 16^a when the 10 valve is adjusted to open the aperture 30. A suitable and efficient means for accomplishing this purpose comprises a link or member 47, one end of which is connected to the extremity of the bar or rod 36 as at 15 48, and the other extremity 49 engages over the shaft 18.

With this improved construction it will be apparent that when the record has been wound upon the roller 16, the key 41 may be 20 adjusted to move the pinion 19 out of engagement with the gear 20 and tighten the chain 25 so that the rotation of the shaft 18 will, through the medium of the chain 25, operate the roller 16^a to re-wind the record 25 thereon and at the same time that the shaft 18 is being adjusted by the rod or bar 36 and link 47, the valve 31 will be adjusted to uncover the aperture 30, thereby relieving the pneumatics 13 of the suction created in the 30 air ducts or channels 10, preventing the pneumatics from operating the piano action and also holding the keys of the instrument against operation. After the record has been re-wound upon the roller 16^a, the key 35 41 may be adjusted so as to disengage the nut or collar 40 and the flexibility of the shaft 18 will return the shaft to its normal position to loosen the chain 25 and to cause the pinion 19 to engage the gear 20, at the 40 same time the suction in the air duct or channel will draw the valve 31 into a position to close the aperture 30 to permit the pneumatics 13 to be operated by the suction in the air ducts or channels 10.

In order that the invention might be fully 45 understood by those skilled in the art, the details of the foregoing embodiment thereof have been thus specifically described, but

What I claim as new and desire to secure by Letters Patent is—

1. In a piano player, the combination of 50 pneumatic actions, means whereby said actions may be exhausted to actuate the same, said means including an air duct having an opening to the outside air, a valve for controlling said opening, a re-winding device, a member for controlling the re-winding device, and a slidable key cooperating with the said member for shifting and locking the member in its shifted position, said member 55 being provided with a projection adapted to engage and open the valve when the member is shifted in one direction.

2. In a piano player, the combination of 60 pneumatic actions, means whereby said actions may be exhausted to actuate the same, said means including an air duct having an opening to the outside air, a valve for controlling said opening, a re-winding device, a member for controlling the re-winding device, a support through which the member projects, said member being provided with a shoulder beyond the support and a key slidably mounted upon the support and adapted to engage the said shoulder to shift the member and lock the same in its shifted position, there being a projection on said member 65 adapted to engage the valve to open the same and to hold the valve open.

In testimony whereof I have signed my 70 name to this specification, in the presence of two subscribing witnesses, on this 30th day of December A. D. 1907.

EUGENE T. TURNEY.
